TYPEWRITING AND LIKE MACHINE

Henry A. Heinrich, Middletown, Conn., assignor
to Remington Rand Inc., Buffalo, N. Y., a cor-
poration of Delaware

Application November 22, 1938, Serial No. 241,838

5 Claims. (Cl. 197—169)

My invention relates to typewriting and like machines, and more particularly to ribbon feed-mechanism for such machines.

In many typewriting machines in which the ribbon feed mechanism is driven from the spring drum it has been customary in practice to effect a feed of the ribbon when the carriage receives a free movement in the direction of its feed, either by a tabulating operation or when the carriage is released and is moved by hand in said direction. This results in comparatively long extents of feed of the ribbon when no impressions are being made and in the uneven use of the ribbon and consequently in relatively heavy impressions at certain points in the writing and relative light imprints at other points in the writing. Moreover, when the ribbon feed mechanism is employed to feed paper ribbons of the so-called carbon or "Hectograph" type where a single run only of the ribbon is effected, such long extents of feed of the ribbon result in a material waste of the ribbon. It also occasionally occurs that during such long extents of feed of a paper ribbon, the ribbon is torn apart due to the abrupt starting and/or stopping of the carriage.

It is one of the main purposes of the present invention to provide improved and highly effective means for overcoming the above mentioned difficulties by automatically rendering the ribbon feed mechanism inoperative during such free movements of the carriage, whether effected by the tabulator mechanism or by the release and positioning of the carriage manually.

A further object of my invention is to provide means under control of the tabulator mechanism and under control of the carriage release mechanism for disengaging the one-way driving connection usually employed to afford feed of the ribbon during the travel of the carriage in a letter feed direction.

A still further object of my invention is to provide means of the character specified above in a machine of the type wherein the carriage release mechanism on the carriage operates to release the carriage by disengaging the feed rack from the feed pinion while the tabulating mechanism operates to release the carriage by disengaging the feed dog from the escapement wheel.

A still further object of my invention is to provide means of the character specified above which may be readily embodied in a typewriting machine of standard construction without modifying, or materially modifying the existing structure, and which is comparatively simple in construction, reliable and highly efficient in use.

To the above and other ends which will hereinafter appear, my invention consists of features of construction, arrangements of parts and

combinations of devices set forth in the following description and particularly pointed out in the appended claims.

In the accompanying drawings, wherein like reference characters designate corresponding parts with a different view:

Fig. 1 is a fragmentary transverse sectional view of a portion of a No. 10 Remington Noiseless typewriting machine equipped with the devices of my invention.

Fig. 2 is an enlarged, fragmentary sectional view of a portion of the ribbon feeding mechanism, the view being taken on line 2—2 of Fig. 1 and viewed in the direction of the arrow at said line.

Fig. 3 is an enlarged, fragmentary, transverse sectional view taken on line 3—3 of Fig. 2 and viewed in the direction of the arrow at said line.

Fig. 4 is an enlarged, fragmentary sectional view taken on line 4—4 of Fig. 2 and viewed in the direction of the arrows at said line.

Fig. 5 is an enlarged, fragmentary view of a portion of the escapement mechanism, the view showing certain parts in section and other parts broken away.

I have shown my invention embodied in the present instance in a machine similar for all essential purposes to the standard No. 10 Remington Noiseless machine in which the features of the present invention may be readily incorporated with but few changes in the existing structure. However it is to be understood that my invention is not restricted to embodiment in such machine, but may be employed in various other types of typewriting and like machines wherever found available.

I have shown in the accompanying drawings only so much of the usual construction of the machine as is necessary to arrive at an understanding of my invention in its embodiment therein.

The distinctions of the machine shown herein over the standard No. 10 Remington Noiseless machine will be hereinafter referred to.

The frame of the present machine includes the usual side plates, the left hand side plate 8 being shown in Fig. 1. These side plates are connected by cross members, such as 9, shown in Figs. 1 and 2, and by rear end plate 10, shown in Fig. 2. The carriage, as shown in Fig. 2, includes the usual platen 12 mounted in carriage end plates, such as the right hand end plate 13, which end plates are secured at opposite ends to a main carriage supporting rail 14. Carriage is mounted for longitudinal letter space travel from side to side of the machine on a case shiftable member or guide rail 15 by crossed anti-friction rollers 16 received in oppositely disposed ways in said guide rail and companion ways in the carriage supporting rail 14.

60

The entire carriage is mounted for substantially vertical case shifting movement by a case shifting rock shaft 18 (Figs. 1 and 2) pivotally supported at its opposite ends to the machine frame. The lefthand pivot screw 19 for the shaft 18, as shown in Fig. 1 is carried by an up-standing portion 20 of the machine frame. The righthand end of the shaft is supported in a like manner. The rock shaft 18 is pivotally connected at spaced intervals with the case shift guide rail 15 by means of arms 22 as shown in Fig. 2. In this figure the righthand rock shaft arm 22 is shown pivotally connected at 23 to a depending lug 24 on the supporting rail 15. The carriage receives a case shift movement by operation of the rock shaft 18 through the usual key controlled case shifting mechanism, which has not been shown in the drawings.

The carriage is impelled in a letter feed direction by a spring drum of the usual construction which is shown in detail in Fig. 2. The spring drum is a hollow construction formed by a cup shaped member 28 and a disc 29 assembled at opposite sides of a centrally disposed enlarged diameter portion of a spindle 30. The spindle 30 is mounted at a still further reduced diameter rear end portion which passes through an opening in a U-shaped bracket 31 carried by the cross member 9 in the usual manner. The hollow interior portion of the spring drum houses a spiral spring 32 which is connected at its inner end at 33 to the spindle 30, and the outer end of the spring 32 is connected at 34 to the cup-shaped member 28 of the spring drum. The usual means are provided for adjusting the tension of the spring 32 by turning the spindle 30, which means includes a pivoted anchor escapement member 36 coacting with a tooth wheel 37, fixedly mounted on the spindle 30. A nut 38 is threaded on the rearward end of the spindle 30 for locking at the adjusted position thereof.

A pull band 40 of the usual construction is wound around the spring drum between flanges formed thereon by a ring 41 secured to the sides 45 of the cup shaped member 28 and a similar ring 42 secured at the opposite disc 29. One end of the pull band 40 is secured in the usual manner to the spring drum and the opposite end is connected at 40a to the right hand carriage end 50 plate 13.

The latter space movement of the carriage under the force of the spring 32 is controlled by the usual escapement mechanism which includes a feed rack 45 carried by pivotally mounted brackets, such as the bracket 46 shown in Fig. 2, which is pivotally mounted at 47 to the carriage guide rail 14 in the usual manner. As may be seen in Fig. 1, the feed rack 45 coacts with a feed pinion 48 carried at the upper end of a substantially vertical disposed feed shaft 44. The lower end of the feed shaft 44 is operatively connected in the usual manner to a tooth escapement wheel 48 which is rotatively mounted in a fixed bracket 49 secured at 50 to the cross member 9.

The usual feed dog mechanism coacts with the escapement wheel 48 to afford a one-tooth movement thereof during a printing operation of each type action. Referring to Fig. 5, it may be seen that this feed dog mechanism includes a normally engaged holding dog 52 and a stepping dog 53. The holding dog 52 is pivotally mounted at 54 on the upper surface of a dog rocker arm 55, and the stepping dog 53 is mounted on the lower surface of the arm 55 by a pivot 56. The dog rocker arm 55 is mounted to rock about a

horizontal pivotal axis (not shown) and is connected in the usual manner for actuation during the printing operation of each type action to disengage the holding dog 52 from the teeth of the escapement wheel 48 and to move the stepping dog 53 into the path of an oncoming tooth.

The usual mechanism for manually releasing the carriage from control of the escapement mechanism to afford a free movement of the carriage in a letter space direction is likewise provided in the present machine. This release mechanism includes the usual carriage release lever mounted at each end of the carriage, as indicated by the righthand lever 58, shown in Fig. 1 and Fig. 2. The lever 58 is pivoted at 59 to the carriage end plate 13 and is connected by a link 60 to the companion feed rack bracket 46. An operation of the carriage release lever 58 rocks the bracket 46 about the pivot 47 to lift the feed rack 45 out of mesh with the feed pinion 48 and allows the carriage to be moved freely in either direction. A contractile spring 61 is provided between the rearward end of the link 60 and a fixed member on the carriage to return the feed rack to normal position.

The usual tabulator mechanism provided in the present machine also includes a means for controlling the escapement mechanism to afford a free run of the carriage in a letter space direction for tabulating purposes. The tabulator mechanism includes the usual tabulator key or bar at the keyboard of the machine and supported on the forward end of levers pivotally mounted intermediate of the machine but the showing of which has been omitted from the drawings. It is to be understood however, that such tabulator key, etc., is or may be of the usual construction and is arranged to afford an upward movement of a rearwardly extending tabulator arm 65 attached upon a depression of the tabulating bar. As may be seen in Fig. 2, the rear end of the arm 65 engages the lower end of an upwardly extending link 66 which is guided at its lower end portion by a guide comb 67, and is connected at its upper end, at 68, to a tabulator stop member 69 which is pivotally mounted at 70 in the usual tabulator frame. The carriage is or may be provided with the usual column stop construction which includes a bar 73 slotted at letter space intervals and mounted beneath a transverse bar 74 which is attached at 75 to each of the carriage end plates 13. A tabulator stop 76 is provided in each of the slots of the bar 73, which stops are arranged in the usual manner to be moved rearwardly to an effective position by a keyset tabulator stop mechanism, which has not been shown. Thus, the upper forward end of the tabulator stop member 69 may be operated to a forward position by a depression of the tabulator bar to coat with a column stop 76 which has been moved to its rearward effective position and arrest movement of the carriage in a letter space direction.

In order to afford a movement of the carriage in a letter space direction upon a depression of the tabulator bar, the usual mechanism is provided for disengaging the holding dog 52 from the teeth of the escapement wheel 48. Thus, as may be seen in Fig. 2, this tabulator release mechanism includes an upwardly extending arm 78 pivotally mounted at 79 on a bracket 80 which is attached to the frame cross member 9, at 80. The arm 80 is provided with a rearward extension 81 which overlies a toe portion 66a of the upwardly extending link 66, and as may be 75

seen in Fig. 5, the upper portion of the arm 18 coacts with the tail portion of the holding dog 52. Therefore at each operation of the tabulator mechanism, the upward movement of the link 66 rocks the arm 18 above its pivot 19 which in turn effects a pivotal movement of the holding dog 52 about its pivot 54 against the force of a spring 32. Thus, the engaging end of the dog 52 is withdrawn from the teeth of the escapement wheel 48 and the carriage is permitted to move in a letter space direction under the force of the spring 32.

The parts of the machine thus far described may be the same in every respect to those provided in the standard No. 10 Remington Noiseless machine.

In the No. 10 Remington Noiseless machine, means are provided for feeding the ribbon longitudinally during a movement of the carriage in a letter space direction. The specific ribbon feed mechanism embodied in such machine includes intermediate driving connection between the ribbon spools and the spring drum together with a one-way clutch arranged to turn the active ribbon spool only during a rotation of the spring drum in a direction affording movement of the carriage in a letter feed direction, and which enables the carriage to be returned without turning the spool.

Before describing this one-way clutch mechanism in detail, the other parts of the present ribbon feed mechanism will be described with reference to Fig. 2. A shaft 90 is mounted in axial alignment with the spindle 30 of the spring drum, which shaft is mounted in bearings in a forward extension 91 of the U-shaped bearing member 31, the member 91 being secured at 92 to the cross member 9 of the machine frame. The rear end of the shaft 90 enters a bearing opening 93 in the forward enlarged portion of the spindle 30 to thereby contribute to the support of said spindle.

Referring to Fig. 1, it may be seen that the forward end of the shaft 90 carries a comparatively large gear 95 which meshes with a smaller gear 96 fixed to a short shaft 97. The shaft 97 is rotatively mounted in parallel relation to the shaft 90 by a bearing provided in the cross member 9 of the machine frame. The forward end 50 of the shaft 97 carries a crown gear 98 fixed thereto, which crown gear meshes with a pinion gear 99 fixed on a transverse by extending reversing shaft 100. The shaft 100 extends through a bearing opening in each of the side plates 8, and each outer end portion thereof carries a small bevel gear, such as the bevel gear 102 shown in Fig. 1.

The transverse shaft 100 in the present machine may be shifted longitudinally to bring either one or the other of the two bevelled gears 102 into meshed relationship with a companion bevel gear mounted at the lower end of associated vertical ribbon spool shaft 104. Thus, at the position of the shaft 100 shown in Fig. 1, the bevel gear 102 meshes with a larger bevelled gear 103 fixed to the lower end of a vertical shaft 104 rotatively mounted in a U-shaped bracket 105 secured at 106 to a side plate 8. The upper end of each of the spool shafts 104 carries a ribbon spool, which, as may be seen in Fig. 1, includes a lower flange 108 and an upper removable flange 109 carrying a finger piece 110. The ribbon 112 in the present instance is wound around a removable core (not shown) mounted 75 between the flanges 108 and 109 to turn there-

with. The ribbon 112 extends from one spool to the other transversely of the machine and passes through a ribbon vibrator 113 which may be of the usual construction adapted to elevate the ribbon in front of the printing point at each 5 operation of a type action. A housing 114 may be attached at 115 to each side plate 8 of the machine to enclose the projecting end of the shaft 100 and the lower portion of the vertical 10 shaft 104.

The specific mechanism shown in Fig. 1 is particularly adapted to the feeding of a carbon paper ribbon, wherein it is desirable to carry a large supply of the ribbon on either of the two spools, and wherein it is desirable to effect an 15 extent of longitudinal feed movement of the ribbon which slightly exceeds a normal letter space distance. However, the devices of the present invention may equally well be applied to the specific ribbon feeding mechanism adapted 20 to feed a ribbon of the conventional fabric construction wherein a lesser extent of longitudinal feed movement is ordinarily effected and a 25 smaller supply of such ribbon is provided on either of the two spools. Such a construction for feeding a fabric ribbon is ordinarily provided in the standard No. 10 Remington Noiseless machine wherein spool shafts, such as the shaft 104 in Fig. 1, are located within the side plates 8, and the pinion gear 99 is driven directly by a 30 crown gear mounted at the forward end of the shaft 90. An automatic ribbon reversing mechanism has not been shown in the present drawing, but such mechanism may of course be provided if desired. 35

As previously mentioned, the intermediate driving connections between the spring drum and the ribbon spools includes a one-way clutch, and in the present instance, this one-way clutch is a pawl and ratchet mechanism employed to 40 operatively connect the spring drum with the drive shaft 90. This clutch construction is shown particularly in Fig. 2 and Fig. 4, wherein it will be seen that a collar 120 having a tooth portion 121 at the rear end thereof is secured 45 by a screw 122 to the rear portion of the shaft 90 adjacent the spring drum. As will be seen in Fig. 4, the ratchet teeth 121 coact with clutch pawls 123 and 124 which are pivotally mounted at 125 and 126 respectively on the front surface 50 of the spring drum member 28. Each of the pawls 123 and 124 is provided with an inwardly extending lug near its pivotal support, which lug enters an associated end of a coiled expansion spring 127. A portion of the spring 127 55 enters an opening 128 in the spring drum member 28.

The free end of each of the pawls 123 and 124 is shaped to enter an interdental space of the teeth 121 and is normally held in such position by the force of the spring 127. This construction operates to drive the shaft 90 in a clockwise direction as viewed in Fig. 4, by a rotation of the spring drum in a clockwise direction. This clockwise direction of rotation of the spring 60 drum occurs during the movement of the carriage in the direction of the feed. However, during a return direction of movement of the carriage, the spring drum rotates in a counter-clockwise direction, and the pawls 123 and 124 70 are cammed outwardly by the teeth 121 to ratchet thereover without driving the shaft 90.

A holding means is provided for preventing a reverse direction of rotation of the shaft 90 which is shown particularly in Fig. 2 and Fig. 3. 75

This holding means includes a hub member 130 having ratchet teeth 131 at the forward end portion thereof and which hub is secured to the shaft 90 by a screw 132. The ratchet teeth 131 coat with holding pawls 133 and 134 which are pivotally mounted at 135 and 136 respectively on a stationary bracket 137. The bracket 137 is provided with an opening receiving the shaft 90, and the bracket may be secured to the bearing block 91, at 138. The holding pawls 133 and 134 are generally similar to the clutch pawls 123 and 124, and may be spring pressed in their normal position to coat with the ratchet teeth 131 by a spring 139, a portion of which spring enters an opening 140 provided in the bracket 137. The free engaging ends of the pawls 133 and 134 coat with the ratchet teeth 131 in the usual manner to prevent counter-clockwise rotation of the shaft 90 as viewed in Fig. 3, but to afford clockwise movement thereof.

A means is provided in accordance with the present invention for preventing unnecessary and undesirable feeding of the ribbon such as ordinarily occurs during carriage movements afforded by a depression of the carriage release key or an operation of the tabulating mechanism. This result is accomplished in the present instance by means under control of the carriage release key 58 and the tabulator mechanism for disengaging the two pawls 123 and 124 from their normal cooperative relation with the ratchet teeth 121 and thereby disconnecting the spring drum from the ribbon spool drive shaft 90.

The specific means shown in the accompanying drawings for obtaining this result includes a throw-out or disconnect member or collar 145 mounted around the collars 120 and 130. An opening 146 is provided in the collar 145 which permits access to the screws 122 and 132 in order to assemble the parts on the shaft 90. The throw-out member or collar 145 is arranged for longitudinal sliding movement on the collars 120 and 130, and the rear end portion of the collar 145 is bevelled at 145^a to form a circular cam surface coating with pins 147 and 148 (see Fig. 4) extending forwardly from the free ends of the pawls 123 and 124 respectively. Thus, when the collar 145 is moved rearwardly from its illustrated position in Fig. 2, along the axis of the shaft 90, the bevelled rearward end 145^a of the collar coacts with the rounded front ends of the pins 147 and 148 to force the free engaging ends of the pawls 123 and 124 out of the path of the ratchet teeth 121, thereby disengaging the spring drum from the shaft 90. The spring 127 acting on the pawls 123 and 124 exerts a sufficient inward force on the pins 147 and 148 to normally hold the collar 145 in its forward position shown in Fig. 2.

In accordance with my present invention a rearward movement of the collar 145 to disconnect the spring drum from the shaft 90 may be effected in one instance upon a release of the carriage by operating either of the carriage release keys 58. The mechanism for affording this result includes a plate member 150 (Fig. 2) having laterally extending ear portions 150^a which enter openings in spaced upwardly extending arms of a bracket member 151 which is attached at 152 to the front face of the case shift guide rail 15. The plate member 150 is thus pivotally supported in front of the feed rack 45, and a laterally offset portion 150^b of the plate member overlies the feed rack, as shown in Fig. 2.

An arm 152 depends from the plate member 150, and the lower end of the arm is pivotally connected to the forward end of a link or push rod 154. A threaded rearward portion of the push rod 154 is provided with a sleeve 155 which is held thereon by nuts 156 and washers 157. As may be seen in Fig. 3, the sleeve 155 on the push rod 154 passes freely thru an opening in the upper end of a vertically disposed arm 158 which is mounted at the lower end portion on 10 a headed pin secured to the bracket 137. The opening in the lower end of the arm 158 which receives the body portion of the pin 158 is sufficiently large to afford a fore and aft pivotal movement of the arm 158, and an opening 159 is provided in the arm 158 which receives the head of the screw 138 employed to mount the bracket 137, thereby maintaining the arm 158 in its upright position.

As shown in Fig. 2 an edge of the arm 158 passes in front of a flange 145^b at the front end of the collar 145, and accordingly a rearward pivotal movement of the arm 158 about the pin 158 will effect a rearward movement of the collar 145 to disconnect the spring drum from the shaft 90. It may be seen that the washers 157 provide an operative connection between the push rod 154 and the arm 158 after the lost motion between said washers and arm has been taken up. Thus, when the feed rack 45 is rocked about the pivot 47 by an operation of the carriage release key, the plate member 150 is rocked upwardly to effect a rearward movement of the lower end of the arm 152 and effect a rearward pivotal movement of the arm 158 through the push rod 154 to disconnect the spring drum from the drive shaft 90. Therefore there will be no feed of the ribbon by a movement of the carriage at this time.

It will be noted that the plate member 150 is mounted on the carriage guide rail 15 and accordingly receives a case shift movement, while the arm 158 operated thereby is mounted on the frame of the machine and accordingly does not receive such case shift movement. The case shift movement of the member 150 relative to the arm 158 is afforded by a shifting of the axis of the push rod 154 to and beyond a position at right angles to the direction of the case shift movement, thereby maintaining the same relation of the parts connected thereby at either case shift position of the carriage.

In accordance with the present invention a rearward release movement of the collar 145 may also be effected in another instance upon the release of the carriage by operating the tabulator mechanism. The mechanism for affording this result includes a transverse bar 165 pivotally mounted at 166 to a fixed bracket 167 as shown in Fig. 1. The bracket 167 may be retained at 60 168 upon the guide comb 67 so that the intermediate portion of the bar 165 overlies the rearward end of the arm 81 which is operated upwardly by an operation of the tabulator actuating link 68.

The free end of the bar 165 is curved upwardly, as shown in Fig. 3, so that the extreme upper end thereof is positioned in front of the flange 145^b of the collar 145. A wedge shaped cam member 170 is secured to this upper end portion 70 of the bar 165 to coat with the bevelled front edge portion of the flange 145^b. A contractile spring 172 extends between the intermediate portion of the bar 165 and a fixed member 173 of the machine frame to return said bar to and 75

resiliently hold it in a normal position. Thus, upon an operation of the tabulator mechanism to release the carriage for free movement in a letter space direction, the bar 165 is operated upwardly about its pivot 166 simultaneously with the arm 81 which operates to release the holding dog of the escapement mechanism, as previously described. Referring to Fig. 2, it may be seen that this upward movement of the free end of the arm 165 operates through the cam member 110 on the bevelled edge 145^b of the collar 145 to effect a rearward movement thereof and thereby disconnect the spring drum from the shaft 90. So, therefore, there is no feed of the ribbon during the tabulating operation.

When a column selecting tabulator mechanism, or a denominational tabulator mechanism is incorporated in the present machine, there will be provided a plurality of key operating means and 20 a plurality of frame stops connected thereto by links such as the link 66 shown in the present arrangement. In such a column selecting or denominational tabulating mechanism, it will be clear that the arm 81 will be arranged to throw 25 out the holding dog 52 and release the carriage upon an operation of any one of the plurality of tabulator keys, and accordingly the bar 165 of the present mechanism also will be operated to disconnect the spring drum from the shaft 90 30 upon an operation of any one of such tabulator keys.

It will be seen that I have thus provided an improved, highly efficient and reliable means for preventing unnecessary and unwarranted longitudinal feed of the ribbon in a typewriting machine during any free movement of the carriage in a letter space direction. In other words, I have provided an improved means under control of the carriage release keys and the tabulator mechanism 40 for rendering the ribbon feed mechanism inoperative. In the present machine, the release keys mounted on the carriage operate to afford a free movement of the carriage in a letter space direction by releasing the feed rack from the feed pinion, while the tabulator mechanism 45 operates to release the carriage by disengaging the holding dog from the teeth of the escapement wheel, and accordingly I have provided automatically 50 operating means for rendering the ribbon feed mechanism inoperative, which means are controlled from each of two separate operating mechanisms of the machine.

A further feature of the present invention 55 which adds to the simplicity of the structure is the utilization of the one-way driving connection or clutch between the spring drum and the ribbon drive shaft as a disconnecting means in the ribbon feeding mechanism. In other words, I 60 have provided means under control of the carriage release keys and the tabulating mechanism for disengaging the usual pawl and ratchet connections employed as a one-way drive or 65 clutch between the spring drum and the ribbon feeding mechanism.

It will be understood, moreover, that the devices of my present invention may be readily incorporated in existing machines without modifying, or materially modifying, the existing 70 structural features thereof.

Various changes may be made in the construction, and certain features thereof may be omitted, without departing from my invention 75 as it is defined in the accompanying claims.

What I claim as new and desire to secure by Letters Patent is:

1. In a typewriting machine, the combination of a carriage having a case shifting movement, carriage releasing means mounted for case shifting movement with the carriage, ribbon feeding mechanism mounted on the frame of the machine, and means controlled by said carriage releasing means for rendering said ribbon feeding mechanism inoperative regardless of the case 10 shifted position of the carriage.

2. In a typewriting machine, the combination of a carriage having both a letter feed movement and a case shifting movement, carriage releasing means mounted on the carriage for movement therewith, ribbon feeding mechanism mounted on the frame of the machine, including a clutch for interrupting the feed of the ribbon, a control member mounted for case shifting movement only with the carriage and operative 15 by said carriage releasing means, and connecting means for operating said clutch by said control member to interrupt the feed of the ribbon regardless of the case shifted position of the 20 control member.

3. In a typewriting machine, the combination of a carriage having both a letter feed movement and a case shifting movement, carriage releasing means mounted on the carriage for movement therewith, ribbon feeding mechanism 25 mounted on the frame of the machine, including a clutch for interrupting the feed of the ribbon, a control member mounted for case shifting movement only with the carriage and operative by said carriage releasing means, and 30 connecting means for operating said clutch by said control member to interrupt the feed of the ribbon regardless of the case shifted position of the 35 control member, said connecting means including a link extending transversely of the 40 direction of case shift movement of the carriage.

4. In a typewriting machine, the combination of a carriage having a case shifting movement relative to the frame of the machine, carriage releasing means mounted for case shifting movement with the carriage, ribbon feeding mechanism mounted on the frame of the machine including a clutch for interrupting the feed of the ribbon, and controlling means for 45 said clutch operative by said carriage releasing means to interrupt the feed of the ribbon regardless of the case shifted position of the carriage, said controlling means including a link 50 which is moved by the case shifting movement 55 of the carriage substantially equal distances each side of a central position wherein it aligns at right angles to the direction of case shifting movement of the carriage.

5. In a typewriting machine, the combination of a carriage, a spring drum therefor, a ribbon feed shaft mounted in a fixed bearing member, clutch means for at times operatively connecting said ribbon feed shaft to said spring drum, a controlling member for said clutch means 60 mounted for axial movement on said feed shaft, key controlled tabulator mechanism, a pivoted arm operated by said tabulator mechanism, and a wedge-shaped member carried by said pivoted arm and operative between said bearing member 65 for the ribbon feed shaft and said controlling member to move the controlling member axially on the feed shaft and disconnect said clutch means.
